UNITED STATES PATENT OFFICE.

WILLIAM E. SELL, OF CANTON, OHIO, ASSIGNOR TO THE SELL HORSE GOODS COMPANY,
OF CANTON, OHIO, A CORPORATION OF OHIO.

HORSE-CHECKING DEVICE.

1,110,650.

Specification of Letters Patent. Patented Sept. 15, 1914.

Application filed May 21, 1910. Serial No. 562,731.

To all whom it may concern:

Be it known that I, WILLIAM E. SELL, a citizen of the United States, residing at Canton, in the county of Stark and State 5 of Ohio, have invented certain new and useful Improvements in Horse-Checking Devices, of which the following is a specification.

My invention relates to checking devices 10 for use in training or breaking horses and also is calculated for use in connection with racing horses; and the objects in view are to provide an overcheck which is devoid of means for chafing and otherwise irritating 15 the horse upon which it is placed and used; to provide means whereby the bit is drawn forcibly upon the roof of the mouth of the animal only when the latter attempts to resist or fight the bit; to provide a chin rest 20 and so locate the same as to allow proper freedom of movement of the jaws whereby the bit may be arranged to avoid contact with the teeth; to provide means for the proper control of the bit while in the mouth 25 and when the horse attempts to bear or press upon the chin rest and furthermore to provide means for guiding and holding the bit straps, which means are so arranged and connected with reference to the bit that 30 the movement of the horse's head will not be interfered with and at the same time allow pivotal movements at substantially right angles to the bit proper, thereby permitting the bit strap supports and guides to 35 adjust themselves so that at no time will the edges of said guides come in contact with the jaws of the horse.

These objects above pointed out together with other objects readily apparent to those 40 skilled in the art, I attain by the construction illustrated in the accompanying drawing, although my invention may be embodied in a variety of other mechanical forms, the construction illustrated being 45 chosen by way of example.

In the accompanying drawing, Figure 1 is a perspective view of a check constructed in accordance with my invention showing the same properly connected to a horse. 50 Fig. 2 is a perspective view of the different parts pertaining to my invention properly connected together so as to be placed in the position illustrated in Fig. 1.

Similar numerals of reference indicate

corresponding parts in all the figures of the 55 drawings.

In the accompanying drawing, 1 indicates the bit, which is provided at its ends with T heads, which T heads constitute upper members 2 and the lower members 3, the extreme 60 outer ends of the upper and lower members being provided with loops or eyes 4 and 5 respectively, which loops or eyes are for the purpose hereinafter described. The upper and lower members extend downward 65 and upward and in vertical alinement so that any pull upon the bit straps 6 will move the bit upward and into proper engagement with the roof of the mouth without causing any rocking movement of the 70 bit 1, this particular feature so far as the non-rocking of the bit being hereinafter described.

To the lower members 3 or more specifically to the eyes 5 is connected the chin rest 75 7 by means of the buckles 8 or their equivalents. It will be understood that, by placing the upper and lower members 2 and 3 of the T heads at the ends of the bit in vertical alinement with each other, the chin rest 7 80 8 will hang directly below the bit 1, so that any upward movement of the bit will cause the chin rest to move with said bit and the pull as between the bit and chin rest will be in straight lines, thereby preventing any lateral strain and at the same time preventing any rocking movement of the bit, also preventing any rocking or oscillating movement of the upper and lower members 2 and 3. This feature is of importance, owing to 90 the fact that any rocking or oscillating movement of the T-heads or ends of the bit has a tendency to irritate and chafe the horse.

To the loops or eyes 4 of the upward extended members 2 are pivotally attached the sheave-blocks 9, which sheave-blocks are provided with the grooved pulleys 10 under which pulleys extend the bit straps 6, which bit straps are connected together by 95 the nose-band 11, to which is attached the upper or finishing strap 12. It will be understood that the nose band may be made separate and attached to the bit straps 6 or may be made integral with the bit straps 100 105 as desired. It will be understood that when any pull is given the bit straps 6 it will have a tendency to lift the bit 1, thereby increas-

ing the pressure of the bit in an upward direction, owing to the fact that the nose-band will hug the nose of the horse. When a pull is given the bit straps it not only lifts the bit 1 but also lifts the chin rest 7, thereby lifting the horse's head and by pivotally connecting the sheave blocks to the upper members of the T-heads the horse can move his head in either direction. It is well understood that if there is any binding of the bit straps such binding has a tendency to produce what is known as side pulls; but by providing the sheave blocks and pivoting the same to the upward extending members of the bit proper there can be no binding of the bit straps or any undue pull of one of the bit straps. By this arrangement the pull is equal upon each bit strap at all times and under all circumstances.

20 For the purpose of providing means for adjusting the bit with reference to the bit straps 6 the strap 14 is adjustably attached to the loop 13 by means of the double looped holder 16 and the metal loop 17, which metal loop is provided with a suitable spud or tongue 18, which spud or tongue can be placed in any of the series of apertures 19.

For the purpose of giving the desired and proper adjustment to the sheave blocks 9, together with the grooved pulleys 10, said sheave-blocks are pivotally joined to the upward extensions 2, thereby preventing any chafing or injury to the horse in case a lateral or side pull is given to either of the bit straps 6. Slidably mounted upon the bit straps 6 is a loop 13 to which loop is attached the central adjusting-strap 14, which strap is connected to the nose band 11 in any convenient and well known manner. The crown piece 15 is of the usual construction and within itself forms no spe-

cific part of the present invention and hence needs no specific description. The present invention having special reference to the construction of the bit 1 together with the aligned upper and lower members forming T-heads at the ends of the bit and the pivoting of the sheave-blocks 9 together with the various directly attached parts.

Having fully described my invention, what I claim as new and desire to secure by Letters Patent, is—

In a horse checking device of the character described, the combination of a bit provided with T-heads, transversely disposed eyes provided upon the lower extremities of said T-heads and laterally disposed eyes provided upon the upper extremities of said T-heads, blocks pivoted to said upper eyes and adapted for universal movement, said blocks provided with grooved pulleys, bit straps located through the pivoted blocks and under the grooved pulleys, the upper extremities of said bit straps joined together forming a nose band, a chin rest secured to the lower eyes and located below the bit and bit strap, an adjustable strap connected to said nose band, a looped holder fixed upon said adjusting strap and adapted for adjustment thereon, and loops carried by said holder, said bit straps slidably mounted through said loops, whereby the nose band is held in predetermined adjustment upon the nose of the horse.

In testimony that I claim the above, I have hereunto subscribed my name in the presence of two witnesses.

WILLIAM E. SELL.
